UNITED STATES PATENT OFFICE.

JOHN H. GOULD, OF PHILADELPHIA, PENNSYLVANIA.

COMBINED RAILWAY-TRACK SUPPORT AND TRACTION-CABLE AND ELECTRIC-CONDUCTORS CONDUIT.

SPECIFICATION forming part of Letters Patent No. 325,531, dated September 1, 1885.

Application filed June 3, 1885. (No model.)

To all whom it may concern:

Be it known that I, JOHN H. GOULD, a citizen of the United States, residing at Philadelphia, in the county of Philadelphia and

5 State of Pennsylvania, have invented a certain new and useful Combined Railway-Track Support and Traction - Cable and Electric-Conductors Conduit; and I do hereby declare the following to be a full, clear, and exact description of the invention, reference being had to the accompanying drawings, which form part of this specification, in which—

Figure 1 is a vertical section. Fig. 2 is a side elevation, and Fig. 3 a plan.

15 My invention has for its object to provide a structure that will form a support or bed for railway-tracks, and also conduits for a traction-cable and for electric conductors, respectively.

20 My invention consists of two parallel tubes united by cross-pieces, one of said tubes being slotted longitudinally and forming a conduit for a traction-cable, the other tube having a man-hole in its outer side and forming a conduit for electric conductors, the two tubes 25 together forming the support for rails fastened thereto or formed integral therewith.

Referring to the accompanying drawings, A and B represent respectively two tubes of metal which are held parallel and in fixed relation to each other by cross-pieces C C. Said cross-pieces may be bolted or otherwise fastened to the tubes, or be formed integral therewith. The tube A is slotted longitudinally on its upper side, as shown at *a*, for the passage of a gripping-lever to engage with a traction-cable running on pulleys *a'* in said tube. The tube B has a man-hole, *b*, in its outer side to permit access to the conductors therein, and 30 said tube may be divided horizontally into compartments *b' b'' b'''*, by means of shelves *b'*, for the reception and separation of different classes of electric conductors—viz., telephonic, telegraphic, and electric-light wires. 40 The man-hole *b* will be large enough to afford access through it to the several compartments in the tube B.

D and E represent railway-rails, which may be formed integral with the tubes A B, or be

fastened thereto. The rail D is arranged in 50 such relation to the slot *a* that the tread of the car-wheel running on said rail will cover said slot.

In laying the structure which constitutes my invention the ground will be excavated in 55 two parallel channels to receive the conduits, leaving a ridge between on which the cross-pieces C C will rest. The tubes A B, which are formed in sections of suitable or convenient length, are then laid in the excavation 60 and the sections fastened end to end, or jointed together in any suitable manner, as by bolting. The earth is then filled in over the cross-pieces and around the tubes and the paving done, the tops of the tubes being on a level 65 with the paving. As the tubes are fastened together by the cross-pieces they will not spread apart, and as said tubes form conduits and the supports for the rails the one tearing up of a street is sufficient for laying a railroad- 70 track, traction-cable, and electric-conductors conduits.

What I claim as my invention is as follows:

1. A combined railway-track support and 75 traction-cable and electric-conductors conduits, the same consisting of two parallel tubes united by cross-pieces, one of said tubes forming a conduit for a traction-cable, and the other a conduit for electric conductors, and 80 both said tubes forming supports for railway-tracks, substantially as shown and described.

2. A combined railway-track support and duplex conduit, the same consisting of two parallel tubes fastened to each other by cross- 85 pieces, one of said tubes having a longitudinal slot in its upper side or top, and the other tube having a man-hole in its outer side, said tubes being adapted to support rails and afford conduits for traction-cables and for electric conductors, as shown and set forth. 90

In testimony that I claim the foregoing I have hereunto set my hand this 27th day of May, 1885.

JOHN H. GOULD.
